ELECTRIC FAN

Thomas F. Helms, Chappaqua, N. Y., and William H. Wentling, Dayton, Ohio, assignors to The Lau Blower Company, Dayton, Ohio, a corporation of Ohio

Application April 19, 1956, Serial No. 41,128

Term of patent 14 years

(Cl. D26—7)

FIG-1

FIG-2

FIG-4

FIG-3

Fig. 1 is a perspective view looking toward the front of an electric fan embodying our new design;

Fig. 2 is a top plan view of the fan of Fig. 1;

Fig. 3 is an elevational view of the back of the fan of Fig. 1; and

Fig. 4 is an enlarged fragmentary section on the line 4-4 of Fig. 1.

The design is characterized by the presence of a relatively narrow panel on the front and rear portions of one side of the device.

What is claimed is:

The ornamental design for an electric fan, substantially as shown and described.
